UNITED STATES PATENT OFFICE.

FRANK E. MARCY, OF SALT LAKE CITY, UTAH.

BALL-MILL.

1,362,334.

Specification of Letters Patent. Patented Dec. 14, 1920.

Application filed March 10, 1919. Serial No. 281,807.

To all whom it may concern:

Be it known that I, FRANK E. MARCY, a citizen of the United States, residing at Salt Lake City, in the county of Salt Lake and State of Utah, have invented certain new and useful Improvements in Ball-Mills, of which the following is a full, clear, and exact description, reference being had to the accompanying drawings, forming a part

10 hereof.

The present invention is directed to improvements in ball-mills, the same being more particularly an improvement on the structures forming the subjects-matter of my U. S. Patents numbered 1,153,238 and 1,153,239, dated September 14, 1915, and 1,226,555, dated May 15, 1917. The objects sought to be attained by the present improvements are identical with those contemplated by the patented structures, the improvements herein however possessing certain structural advantages not present in the patented machines. Among the novel features possessing these advantages may be 20 mentioned the grate sections formed by the welding of the terminals of the grate bars; the peripheral slots formed in the walls of the drum for the insertion of the several grate sections; the special sheet liners for the discharge heads and lifters; and other details the advantages of which will be fully apparent from the following detailed description in connection with the accompanying drawings in which—

30 Figure 1 represents an end elevation of a mill showing one form of my improved grate, viewed from the feed end, the scoop feeder being cut off and part of the feed head broken away; Fig. 2 is a side elevation 40 of the mill with parts in longitudinal section; Fig. 3 is an enlarged vertical cross-section on the line 3—3 of Fig. 2 showing a portion of the grate and discharge head to which the same is secured, and a portion of the sheet liner for the head and lifters; Fig. 4 is an enlarged plan of the portion of the 45 periphery of the drum in which the slot is formed for receiving the grate sections, a portion of the cover plate for the slot being removed; Fig. 5 is a plan of the center grate section broken at the middle; Fig. 6 is a plan of two bars welded together at their 50 ends; Fig. 7 is an enlarged longitudinal sectional detail on the line 7—7 of Fig. 5 showing the position of the welds between the terminals of two bars; Fig. 8 is a cross-sec-

tion on the line 8—8 of Fig. 6 showing the weld between the bars; Fig. 9 is a perspective of one end of two welded bars taken from the center of the middle grate section, 60 the bars being of equal length at that point being disposed on the diameter of the grate; Fig. 10 is a cross-sectional detail on the line 10—10 of Fig. 3 showing one of the forms of sheet head liner for supporting the grate; 65 Fig. 11 is a similar section showing a slight modification of liner; Fig. 12 is a view similar to Fig. 3 showing a modified form of grate composed of a series of grate sectors; Fig. 13 is a cross-sectional detail on the line 70 13—13 of Fig. 12; Fig. 14 is a combined side elevation and longitudinal section of one end of a drum showing a grate-receiving peripheral slot extending around one-half of the circumference of the drum and showing a 75 one piece grate; and Fig. 15 is a vertical cross-section on the line 15—15 of Fig. 14.

Referring to the drawings, and for the present to Figs. 1 to 10 inclusive, 1, represents the outer shell of the drum or tumbling barrel (or equivalent tubular container), and 2, the liner thereof, said drum being provided with a feed head 3 and a discharge head 4, said heads being formed with the hollow feed and discharge trunnions 5 and 6 respectively as well understood in the art. In the type of mill before us, the inner face of the discharge head 4 is provided with a series of radial blades or lifters 7 against which bears the disk-like 80 screen or grate forming one of the terminal walls of the crushing compartment C. In the present embodiment of my invention this grate is composed of a plurality of sections, said sections taking on the form of 85 segments a (there being five segments in the present case), each segment or section comprising a series of rolled grate bars 8 provided with spacing lugs or pads 9, the ends 90 of the bars being welded together on the 100 sides along their outer corners, that is to say, the corners adjacent to or facing the lifters 7, against which the grate bears and by which it is in a large measure supported. The welds w are clearly indicated in Figs. 105 5 to 8 inclusive. In this type of mill, a sectional grate composed of a series of rolled bars welded together at the ends so as to form a plurality of sections, so far as I am aware, is new, the object of locating the 110 welds at the outer or "lower" corners of the bars being that the grate has a tendency to

wear, and in practice actually does wear "down" to a concave surface substantially as indicated by the curved dotted line x in Fig. 7. By thus locating the welds w out of the range of action of the attrition bodies of the mill, the grate bars will hang together as a unit until the particular section or segment of which they form a part is discarded and replaced by a new section. To insert 10 the grate sections into the crushing compartment of the drum I provide the latter with a peripheral slot O of sufficient length to admit the full width of the widest section, the side sections being inserted first 15 and then pushed to one side, then the intermediate sections are inserted and pushed against the side sections, and finally the middle section is inserted, the last section fitting snugly between the intermediate sections 20 and remaining directly under the slot O . The latter is then covered by a curved or arcuate plate 10 of T-shaped cross-section, the body of the plate entering the slot and the flanges of the plate overlapping the 25 walls of the slot, the terminals of the flanged portion being bolted to the wall of the drum. The grate thus built up is then fastened rigidly in position by the screw-bolts 11 disposed circularly about the periphery of the 30 drum the same as shown in my Patent No. 1,153,239 aforesaid. Since the slot or opening O is disposed in the plane of disposition of the grate, all that is necessary when a grate is to be placed into the mill, is to drop 35 the grate sections through the slot (the drum being previously turned to bring the slot on top), push the side and intermediate sections to one side and the center or middle section into place, clamp down the cover 40 plate 10 and the job is finished. In the same way worn-out grate sections or a worn-out grate may be removed through the slot O . The installation of a grate may thus be made in a minimum amount of time and 45 with little effort or expenditure of energy.

In my present improvement I provide the discharge head and its radial lifters with a sheet metal liner, the same being composed of a series of radial sections or sectors 12 disposed along the inner face of the head 4, then bent up (inward) at the sides to engage 50 the sides of the lifters 7, one of the sides of the liner being folded, or brought up over the inner radial edge of the lifter, the opposite side stopping flush with the radial edge of the adjacent lifter (Fig. 10), the fold of one liner section covering the radial edge of a lifter overhanging said edge sufficiently to overlap the edge of the upturned side of 55 the next liner section terminating flush with the edge of the lifter. The folding of the sheet liner over the inner radial grate-supporting edge of the lifter is not necessary in all cases, and in Fig. 11 is shown a modified form of liner composed of sections 12'

the radial edges of whose upturned or in-turned sides all terminate flush with the radial edges of the lifters. In both forms the liner sections are secured to the lifters by pins or pegs h as shown. The present 70 mill is provided with a conventional form of scoop feeder 13, the drive 14 being on the feed end of the mill.

The grate or screen need not necessarily be composed of sections which are segmental in form, but may be built of sections in the form of sectors a' as shown in the modification in Figs. 12 and 13. In that case the individual grate bars 15 and pads 16 are of rolled metal and likewise welded 80 at their ends, the welds w' being on the side of the bar and at the lower or outer corners thereof, that is to say, the corners adjacent the lifters 7 which support the gate. In this modification the concave surface to 85 which the grate wears down is indicated by the curved dotted line x' in Fig. 13, it being apparent that the welded corners will be permanently out of range of action of the attrition bodies tending to disintegrate the 90 grate, whereby the grate sector will remain as a unit until discarded. Where a grate is composed of sectors a' the peripheral slot O can not be availed of to advantage and in that case the grate sectors are installed either before the two sections of the outer shell of the drum are assembled (the shell 1 being usually in two sections), or they may be inserted through a suitable man-hole where the mill otherwise has been 100 assembled. Where a grate composed of sectors a' is employed, the sectors are secured to the lifters by bolts 17 passed through the clamping bars 18 inserted between the beveled radial meeting edges of 105 adjacent sectors, said edges resting on the radial edges of the lifters. In neither of the forms of grate above described is it necessary to extend the sheet metal liner 12 (12') over the inner face of the ledge 19 110 formed on the inner wall of the shell 1 and connecting the outer ends of the lifters 7, it being sufficient to apply it to the inner face of the head 4 and to the lifters 7. If desired however, the sheets 12 may be ex- 115 tended to cover said ledge 19 and it would be fully within the spirit of my invention to do this.

Where a grate is built up of a plurality of segments such as a , a short peripheral slot O of a length sufficient to allow a segment to be passed into the mill answers the purpose. There may be instances however where it might be desirable to employ a one-piece grate 20 as shown in the modification illustrated in Figs. 14 and 15. In that event resort would be had to a peripheral slot O' extending around circumferentially fully one-half the periphery of the shell, a corresponding semi-circular cover 120

125

130

plate 10' being availed of after the grate was dropped into position. Where a one-piece grate is desirable, the semi-circular slot O through which the grate can be directly dropped into position is most ideal, and scarcely any time need be lost in installing a grate of this kind through such an opening.

In all the forms of mill here considered, the grate component of the mill is supported by the lifters 7, and held against rotary displacement by the screw-bolts 11 which clamp the several sections together and to the shell, the grate being further guarded on the side facing the crushing compartment by the adjacent end of the wall liner 2. The use of a peripheral slot or opening disposed in the plane of disposition of the grate, through which the grate or sections thereof may be dropped into position without moving the same out of said plane is a decided advantage, tending to economy and saving of time and labor. The one-piece grate shown in Figs. 14 and 15 is only by way of example, and other forms of grate may be employed. For instance, a one unit grate might be formed of welded bars such as shown in Figs. 1 to 3 and Fig. 5. By welding together the outside bars of the several sections *a* of the first form of grate above described, we could obtain a one unit grate which would be a full equivalent of the one piece grate shown in Figs. 14 and 15.

The essential component parts of a mill of the type here described are the drum (shell 1 and wall liner 2), the feed and discharge heads, and the grate, the absence of any one of which would destroy the integrity of the mill; and while in the present example the heads are shown integral with the shell sections, it is apparent that the heads (3, 4,) may be separate members bolted or otherwise secured to the shell.

Little need be said as to the operation of the mill. The material is fed to the mill through the hollow trunnion 5 into the crushing compartment C, where it is ground during the rotation of the mill about its axis, the fine particles passing through the screen or grate and entering the radial compartments between the lifters 7. The crushed material is conducted through the discharge trunnion 6, whence, as a rule, it is conducted to a suitable classifier which returns the coarser sands back to the mill for regrinding, the fines being subjected to whatever treatment may be necessary for the recovery of the metal or other values therefrom.

Features shown but not alluded to herein

are well understood in the art and require no description in the present connection.

Having described my invention what I claim is:

1. In a mill of the character described, a crushing compartment, a grate comprising a plurality of rolled bars spaced apart forming one of the walls of said compartment, suitable attrition bodies in the crushing compartment, the bars being welded to one another at the ends at points beyond the range of action of the attrition bodies.

2. In a mill of the character described, a crushing compartment, a grate composed of spaced bars and forming one of the walls of said compartment, a support for the grate on the side facing away from the crushing compartment, the ends of the bars being welded together at only one side of each and at a point adjacent the grate support.

3. In a mill of the character described, a crushing compartment, attrition bodies in said compartment, a grate composed of a plurality of sections each comprising a series of rolled metal bars provided with spacing pads, a support for the grate on the side opposite from that facing the crushing compartment, the ends of the bars being welded only at the corners of the bars on the side of the grate adjacent the grate support whereby the welds are permanently out of the range of action of the attrition bodies.

4. In a mill of the character described, a drum, a screen grate disposed across the rotation axis thereof, there being a peripheral slot in the wall of the drum disposed in the plane of disposition of the grate for the insertion of the grate into the mill.

5. In a mill of the character described, a discharge head provided with radial lifters, and a sheet metal liner bent to cover the inner face of the head and the sides and radial edges of the lifters.

6. In a mill of the character described, a discharge head provided with radial lifters, and a sheet liner comprising a series of radial sections each covering an area of the inner face of the head bounded by two lifters, and bent to protect the sides of the bounding lifters facing said area, one of the bends being brought over the radial edge of the lifter and projecting sufficiently beyond it to overlap the edge of the upturned side of the next succeeding liner section.

In testimony whereof I affix my signature, in presence of two witnesses.

FRANK E. MARCY.
